UNITED STATES PATENT OFFICE.

JOHN S. HOLLIDAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRIC RELAY AND MOTOR FOR USE THEREIN.

1,310,622.

Specification of Letters Patent. Patented July 22, 1919.

Application filed July 31, 1916. Serial No. 112,222.

To all whom it may concern:

Be it known that I, JOHN S. HOLLIDAY, a citizen of the United States, residing at Wilkinsburg, in the county of Allegheny and 5 State of Pennsylvania, have invented certain new and useful Improvements in Electric Relays and Motors for Use Therein, of which the following is a specification.

My invention relates to electric relays and 10 motors for use therein.

One object of my invention is to provide a relay immune to current of a predetermined frequency. Other objects of my invention will appear in the following description. 15

I shall describe one form of relay embodying my invention, and also one way of using the same in a railway signaling system, and will then point out the novel features there- 20 of in claims.

In the accompanying drawings, Figure 1 is a diagrammatic view showing one form and arrangement of railway signaling circuits comprising one form of relay R embodying my invention. Fig. 2 is a vector diagram showing for one frequency the currents in the various members of relay R. Fig. 3 is a similar vector diagram for current of said predetermined frequency, Fig. 4 25 is a diagrammatic view showing the electrically equivalent circuit for relay R.

Similar reference characters refer to similar parts in each of the views.

Referring first to Fig. 1, reference characters 4 and 5 designate the track rails of an electric railway, which rails are divided into sections by insulated joints 2. In the drawing I have shown only one section X-Y and the beginning and end respectively of 40 the two adjoining sections. For the control of traffic through section X-Y, I provide a signal S having a semaphore arm 20, which, when in the vertical position, as shown, indicates "proceed," and which, when in the horizontal position, indicates "stop." These 45 positions of the signal arm are controlled by a relay R, through the following circuit: from a battery E, through contact finger 6 of relay R, wire 8, operating mechanism of signal S (not shown) and wire 7 to battery E.

Relay R operates on the induction principle and comprises a movable member 10 for operating contact point 6 which member

is responsive to currents in windings 11 and 55 12, provided the current in one winding is sufficiently displaced in phase from the current in the other. Relays of this type are well known in the art and need no further explanations. Windings 11 and 12 are connected in series and derive their current from a track circuit which comprises the track rails 4 and 5, a source of signaling current connected to these rails adjacent one end of section X-Y, and the windings 11 and 12 connected to these rails adjacent the other end of the section. As here shown, the source of signaling current is a transformer M, the primary of which receives signaling current from an alternator H through a transmission line N. The signaling current flows from the transformer M through the track rails to windings 11 and 12 in series.

For producing a difference in phase of 75 the current in winding 12 relative to the current in winding 11, I provide a shunt around winding 11, which shunt comprises an open core transformer T the primary of which is connected in parallel with winding 11 and 80 to the secondary of which is connected a condenser 30. Referring now to the vector diagram Fig. 2, vector OE represents the voltage impressed on winding 11. For purposes of this vector diagram, the shunt circuit around winding 11 may be considered, 85 as shown in Fig. 4, as a parallel connection of the condenser 30 and an inductance T_m , said inductance having such characteristics that the current taken thereby is the same 90 as the magnetizing current of the transformer T. The current in winding 11, shown by vector OA, is in phase with the voltage OE because the winding 11 is made with a substantially unity power factor. 95 Because of its open magnetic circuit, the current in inductance T_m , or the exciting current of the transformer, is rather large and lags considerably behind the phase of voltage OE, as shown by vector AC. The 100 current taken by the condenser 30 is of substantially zero power factor and leads the voltage by approximately ninety degrees, as shown by vector CB. The current in winding 12 is evidently the vector sum of the 105 three currents above-mentioned, and is represented by the vector OB. It is apparent that the current in winding 12 is displaced

in phase from the component thereof in winding 11 by a considerable angle in counterclockwise direction. The rotor 10 of the relay R responds to these currents by 5 operating contact finger 6 into engagement with its contact point so that the semaphore 20 of signal S is raised to the vertical position and indicates "proceed."

When a vehicle V enters the track section 10 X—Y, the wheels and axles thereof form a path of low resistance between the rails 4 and 5 so that the current in the relay windings is reduced to an amount insufficient to hold contact finger 6 against its contact 15 points. The contact, therefore, opens and breaks the circuit for signal S, so that the semaphore 20 of the signal drops to the horizontal position and indicates "stop." Thus it appears that relay R is responsive to the 20 signaling current in the track circuit of section X—Y and controls the signal S to indicate "proceed" or "stop" according to the presence or absence of vehicles in section X—Y.

25 Propulsion current for the operation of the cars or trains along the railway is furnished by an alternator G, one terminal of which is connected to a trolley wire or third rail L, and the other terminal of which is 30 grounded to the track rails. This current differs in frequency from the signaling current, the usual frequency of the propulsion current being 25 cycles and that of the signaling current 60 cycles. The propulsion 35 current flows from one terminal of the generator through wire L, vehicle V, track rails 4 and 5 in parallel to the other terminal of the generator G. Impedance bonds I are provided for passing the propulsion 40 current around the insulated joints without interfering with the flow of the signaling current as well understood in the art. In flowing through the vehicle the current drives the propulsion motors which I have 45 not shown on the drawing.

For a variety of causes, to mention only unequal bonding of the track rails, it may happen that for the propulsion current the potential of one track rail in section X—Y 50 is higher than the potential of the other rail, so that a part of the propulsion current flows from one track rail to the other through the windings 11 and 12 of relay R.

The 25 cycle voltage in winding 11 of 55 relay R is shown in Fig. 3 by vector O'E', which for convenience is chosen equal to the voltage OE in Fig. 2. The current in winding 11 resulting from this voltage is shown by vector OA'. The current in inductance T_m , or the exciting current of 60 transformer T, represented by a vector A'C', is considerably larger than the exciting current of the transformer at 60 cycles, approximately in the ratio of 60 to 25. On

the other hand, the current for condenser 65 30, represented by vector C'B', is decreased in substantially the same ratio. The phase of the resultant current O'B' in winding 12, is approximately the same as the phase of the current OA' in winding 11, preferably 70 differing therefrom by a small angle in clockwise direction. This causes a slight torque in clockwise direction on member 10, which torque tends to assist gravity in opening the relay contact and is therefore on 75 the safe side. The relay is therefore immune to the propulsion current, in that the presence of this current in the relay windings cannot cause the signal S to give a clear or proceed indication. It will be seen, 80 therefore, that when the section X—Y is occupied by a car or train, even if there should be a considerable difference of potential of the propulsion current across the terminals of relay R this relay would not be 85 operated thereby to close its contact 6, and in fact the presence of the propulsion current would tend to assist gravity in holding this contact open.

Moreover, even if the arrangement of the 90 apparatus shown in Fig. 1 is disturbed, the propulsion current cannot cause the relay to close its contact because the current in winding 12 cannot under any circumstances differ in phase from the current in winding 11 95 by a counterclockwise angle. For example, if transformer T should become disconnected from winding 11, the propulsion current would be of the same phase in both windings. Again, if the condenser should 100 become disconnected from transformer T the 25 cycle current in winding 12 would be represented in Fig. 3 by a vector O'C'. This current, being at a clockwise angle to the current in winding 11, would tend to 105 open the relay contact. If several turns of the primary of transformer T should become short-circuited, as indicated on the drawing by a dotted connection 31, or if several turns of the secondary winding of 110 this transformer should become short-circuited as indicated by dotted connection 32, the current flowing in these connections would be represented by a vector B'D', and the resultant current in winding 12, shown 115 by a vector O'D', would also be unable to effect a closure of the contact of the relay. Thus it appears that any derangement of the apparatus causes a failure on the side of safety, it being impossible for the propulsion current to close contact 6 and thus cause a proceed indication of the signal.

Although I have herein shown and described only one form of relay embodying my invention, it is understood that various 125 changes and modifications may be made therein within the scope of the appended claims without departing from the spirit

and scope of my invention. Having thus described my invention, what I claim is:

1. A relay comprising two windings connected in series, in which windings a plurality of currents differing in frequency may flow at different times, means shunted across one of said windings for affecting the phases of said currents in the other winding, said means comprising an open core 5 transformer and a condenser connected to the secondary thereof, a member responsive to currents displaced in phase in said windings and a contact governed by said member.
2. A motor immune to current of a predetermined frequency comprising two windings connected in series, a transformer having a high magnetizing current connected across one of said windings, a condenser connected to the secondary of said transformer, said condenser and transformer being so proportioned that for current of a predetermined frequency the current in the second winding is substantially in phase with the current in the first winding, and a 10 movable member responsive only to currents in said windings displaced in phase.
3. A motor immune to current of a predetermined frequency comprising two windings, an open core transformer whose primary is connected across one of said windings, a condenser connected in circuit with the secondary of said transformer, said con-

denser and transformer being so proportioned that for current of a predetermined frequency the current in the second winding is substantially in phase with the current in the first winding, and a movable member responsive only to currents in said windings displaced in phase. 35

4. A relay comprising two windings connected in series, a transformer comprising a magnetic core having an air gap therein, the primary winding of said transformer being connected in parallel with one of said relay windings, a condenser connected in 40 circuit with the secondary of said transformer, a movable member responsive to currents in said relay windings when said currents are displaced in phase, and a contact controlled by said member. 45

5. An alternating current motor comprising two windings connected in series, a transformer whose primary is connected across one of said windings, a condenser connected in circuit with the secondary of said transformer, and a movable member responsive to currents in said windings displaced 50 in phase.

In testimony whereof I affix my signature in presence of two witnesses.

JOHN S. HOLLIDAY.
